CHAIN AND LOCK COMBINATION

Sylvan Engel, Brooklyn, N. Y.

Application March 25, 1935, Serial No. 12,982

12 Claims. (Cl. 70—14)

My invention relates to chain locks, and in more detail, to a combination of a lock with a chain attached which functions on a door permitting the door to be opened partially on a twist of the lock knob in one direction and then permitting the door to be opened fully on a reverse twist of the knob.

At present there is no structure combining the locking and barring functions in a single unit, whereby a single actionable releasing mechanism functions to release both the locking and barring means individually and consecutively by reverse movements of the releasing means. There is, however, a chain bar which is made up of a chain attached to the jamb of the door frame and the other end of the chain is supplied with a grooved element suitable for sliding in "a way" in the door. This chain bar must be left released normally in order to permit a person to open the door from the outside and it must be released in order to open the door from the inside when permitting a person to enter. Thus, the chain must be left or placed in a detached position almost continually and often results in a lack of protection when it is most needed. In addition to the above type of locking and barring mechanisms there is a type comprising a combination, a locking and barring unit which is controlled by two releasing mechanisms, one of which releases the locking means and the other, the barring means. This type is not fool-proof because the releasing of the barring means can also release the locking means. In addition this mechanism requires the use of both hands and is constructed with a complexity of parts not present in the described and claimed structure below.

The purpose of my invention is to provide a combined lock and chain which functions in such a way that the door to which it is attached cannot be opened from the inside unless the chain is in a position to function.

A further object of my invention is to provide a combined chain and lock which will permit the door to which it is attached to be opened from the inside only to the extent of the chain on the initial turning of the lock knob and will release the chain and permit the door to be opened completely on a further turning of the knob in a second direction.

Another object of my invention is to provide a chain and lock combination which, when attached to a door, will permit the door to be opened from the inside only to the length of the chain on the initial turning of the lock knob,

but which will allow the door to be opened completely from the outside by turning the key to the proper opening position.

A further object of my invention is to provide a lock and chain combination for a door in which the chain automatically immediately assumes a position from which it will function on the closing of the door.

I accomplish these and other objects by providing a lock for a door comprising two tongues operated by arms on a knob in such a way that when the knob is turned in the one direction it releases the tongue held in a locking groove on the door jamb and when the knob is turned in the opposite direction it releases the other tongue which has been held in one end of a chain, the other end of the chain being permanently fastened to the door jamb.

Further and more specific objects, features and advantages will more clearly appear from the detailed description given below taken in connection with the accompanying sheet of drawings which forms a part of this specification.

Figure 1 is a plan view of my lock with the cover piece removed; Fig. 2 is a section along the line 2—2 of Fig. 1; and Fig. 3 is a section generally along the line 3—3 of Fig. 1 showing the door opened and the lock operating with the chain extended.

In the drawing, my locking device is constructed in two parts, the first part 3 is secured to the door and the other part 4 is secured to the door jamb 2. The part 3 which contains the locking and moving mechanism comprises the base plate 5 on which the moving mechanism 6 rests which closes and opens the lock, the cam parts 7 which permit a key to open the lock without the chain functioning, and the knob and covering part 8.

A base platform 9 raises and supports the part 3 carrying the locking and moving mechanism at a height so that part of the base plate with part of its moving mechanism extends over the part 4 attached to the door jamb. This base platform 9 extends around the edges only of the part 3 and can be eliminated if the part 4 is countersunk into the door jamb.

The base plate 5 is constructed with side walls 10 which guide the moving mechanism 6 and is provided near its tail end with an opening 11 and near its head end with openings 12 which are positioned directly over the part 4 attached to the door jamb. The purpose for which the openings 11 and 12 are to be used will be described hereinafter.

The moving mechanism 6 comprises two 55

tongues or plates 13 which rest on the base plate, the front ends 14 of the plates extending part way over the openings 12. At about the mid part each plate is provided with a pin 15 and near 5 their rear end the plates are provided with the pins 16. The plates are also provided with a cut out portion 17 which corresponds to and is directly over the opening 11 in the base plate. The pins 16 are to the rear of and near the cut out 10 portion 17. The front ends 14 of the plates are beveled so as to slide over extensions on the part 4 attached to the door jamb. The inner sides of 15 the plates rest adjacent each other and the outer sides are near the side walls 10 of the base plate, thus each plate can slide back and forth in a "way" formed by one side wall 10 and the side of the other plate.

The cam 18 is placed above the plates and is provided with an eccentrically placed stem 19 20 which extends through the cut out part 17 of the plates and through the opening 11 in the base plate. The end of this stem is provided with an elongated opening 20. The cam is positioned near the pins 16 so that on the turning of the cam its 25 edge strikes the pins and forces the plates backward. As the pins are placed close together they are struck practically simultaneously and the plates will move backward almost together.

To turn the cam 18 a cylinder lock 21 on the 30 outer side of the door is provided with an extension piece or extension bar 22 which extends from the lock barrel into the shaped opening 20. Thus by turning the extension piece of the lock the cam turns and the pins 16 are struck to force back the 35 plates or tongues 13. In order for the cylinder lock to function easily with the cam said lock is centered in line with the stem 19 about which the cam turns.

The covering part 8 comprises a cover plate 23 40 which extends over the base plate and its side 10 and forms the outside of the part 3 of the device. This cover is provided on its outer side with a knob 24 which has a stem or shaft projecting through the cover to the inside of the part 3 and 45 forming the extension or rollback 25.

This extension is provided with the side extending arms 26 which are close to and capable of striking the pins 15 when the knob 24 is turned in reverse directions. The pins 15 are placed one 50 on each plate a little to the back of and one on either side of the knob and its extension so that the turning of the knob to the right releases or 55 forces back one of the plates or tongues and the turning of the knob to the left forces back the other tongue or plate. As a continuous turn in one direction forces one plate back and the other forward both plates can only be forced backward by a reversal of the direction of turning of the knob.

60 A piece 27 placed at the front end of the part 3 is provided with a raised part 28 and with an extending lip 29. The extending lip rests just high enough above the base plate 5 to permit the tongues 13 to slide back and forth. The raised 65 part 29 extends from the front of the device to the rear of the openings 12 and forms a box like encasement 30.

Two pins 31 are placed on the lip part 29 and carry coiled springs 32 which are fixed at their 70 other ends to the pins 15 on the plates or tongues. As the pins 31 on the lip part are to the front of the pins 15 on the tongues the tongues are forced forward toward and into the box part 30 and partly over the openings 12 in the base plate. 75 The plate can never be forced more than half

way over the openings 12 as in this position the springs become closed and occupy the complete distance between the pins 15 and 31.

Thus the part 3 of the device has two tongues which extend normally part way over the openings 5 12 in the base plate but which can be forced backward in either of two ways. The first is by turning the key in the lock on the outer side of the door and forcing both tongues back at the same time; and the second is by turning in two 10 directions the knob on the inner side of the door and forcing back each tongue individually.

The part 4 fixed on the door jamb comprises a case 33 carrying inside it a spring 34 and a chain 35 and a stop piece or latch block 36 fixed on the 15 outside. The case is placed on the door jamb in a position so that the stop piece or latch block 36 rests directly in line with one of the openings 12. As the case and the platform of the part 3 are of the same height, the piece 36 extends into the 20 opening 12.

The stop piece is provided with a grooved part 37 near its base and a sloping cone shaped head 38 corresponding and opposite to the beveled part of one of the tongues, thus permitting the tongue 25 to slide backward when they contact on the shutting of the door. When the door is completely shut the stop piece extends upward into the box like encasement while the tongue is forced forward by its spring into the groove of the stop piece and 30 locks the door.

The spring 34 is attached at one end to the part 4 and to the door jamb by a screw 39 which extends through the part 4 and spring into the door jamb. The other end of the spring 35 is fastened to the end of the linked chain 35. The free end of the chain extends through an opening in the case and terminates in a head piece 40 similar to the stop piece 36. When the spring is contracted the chain is completely inside 40 and the head piece rests on the outside of the case near the stop piece.

The stop piece 36 is positioned directly in line with the other of the openings 12 and under the other tongue 13 and functions to catch its tongue 45 in the same manner as the head piece. However, this head piece and tongue combination will bar the door instead of locking it, the head piece and chain running out of the case as the spring expands on the opening of the door. When the 50 spring is expanded to its limit, the door cannot be further opened until the knob is turned to release the tongue from the head piece. When this is done, the spring 34 contracts and pulls the chain back into the case 33 until the head 55 piece rests in its position on the outside of case 33.

When the door is closed both tongues are caught in the grooves 37, one in the head piece and one in the stop piece. When the door is 60 opened from the inside the knob must be turned first in the direction which will push back the tongue held in the stop or latch piece thus releasing the locking means and permitting the door to be opened to the extent of the chain. To open the door wide the knob must now be turned 65 in the opposite direction from which it had previously been turned thus releasing the tongue holding the chain head piece. Thus to open the door from the inside the knob must be turned, the door slightly opened, and the knob turned in the 70 reverse direction. The door must be held opened between the turnings of the knob, otherwise on the second turning the tongue co-acting with the stop piece is pulled forward by its spring and re-locks the door.

The door is opened from the outside by turning the key in the lock which in turn through the extension and cam releases both tongues and permits the door to be opened widely at once.

5 When the door is shut both tongues are automatically slid into their grooves in the head and stop piece respectively and the door is latched or locked and the chain is ready to function as a barring means. Thus the normal position is for 10 the door to be chained as well as locked at all times.

A further modification in structure can be made by replacing the spring 34 with a weight or a leaf type of spring.

15 As the details described in the drawing show only one form of my invention and since many changes and modifications may be made in the same invention without changing or departing from the spirit and scope of the idea, I desire 20 to cover all modifications, forms and embodiments coming within the language or scope of any one or more of the appended claims.

I claim:

1. A locking and barring mechanism for a door 25 consisting of a chain, a spring attached to the chain and to the door jamb, a headpiece on the chain provided with a groove, a stop piece on the door jamb provided with a groove, two reciprocable movable tongue mechanisms on the door, 30 two spring mechanisms forcing the tongues into the grooves of the headpiece of the chain and stop piece, roll back means for individually releasing said tongues by reverse movement of said roll back means.

35 2. A locking and barring mechanism for a door consisting of a chain, a spring attached to the chain and to the door jamb, a headpiece on the chain provided with a groove, a stop piece on the door jamb provided with a groove, two oppositely 40 movable tongue mechanisms on the door, two spring mechanisms forcing the tongues into the grooves of the headpiece of the chain and stop piece, turning means capable of releasing only individually the tongues by reversing the direction of operation of the turning means.

45 3. A locking and barring mechanism for a door consisting of two parts, one attached to the door jamb having a chain, a spring attached to the chain and to the part, a headpiece on the chain 50 provided with a groove, a stop piece provided with a groove, and the other said part attached to the door having two reciprocable tongue mechanisms, two spring mechanisms capable of forcing the tongues into the grooves of the head piece of 55 the chain and the stop piece, reversely movable releasing mechanism operable from the inner side of the door adapted by reverse movement, to, individually and consecutively release the tongues, key operated lock means extending through the 60 door from the outer side, a connecting bar on and operated by said lock means for releasing both the tongues from their grooves practically simultaneously.

4. Locking and barring mechanism for a door 65 comprising one part attached to the door jamb and the other part attached to the door, the part attached to the door jamb having a fixed head piece with an opening therein and a limitedly movable head piece having an opening there- 70 in, the part attached to the door having a tongue capable of entering the opening in the fixed head piece, a spring forcing the tongue piece into the opening in the fixed head piece, a second tongue capable of entering the opening in the limitedly 75 movable head piece, a second spring forcing the

second tongue into the opening in the limitedly movable head piece, projecting pins on said tongues, arm means pivotally mounted between the pins of the tongues and capable of forcing the tongues backward to release both the said 5 tongues from said locking and barring means the turning of the arm mechanism in a clockwise direction striking the pin of the first tongue, to push the tongue back and release it from the fixed head piece, and the turning of the arm 10 mechanism counter-clockwise striking the pin of the second tongue mechanism to push the tongue back and release the tongue from the limitedly movable head piece.

5. Locking and barring mechanism for a door 15 comprising one part attached to the door jamb and the other part attached to the door, the part attached to the door jamb having a fixed head piece with an opening therein and a limitedly movable head piece having an opening 20 therein, the part attached to the door having a tongue capable of entering the opening in the fixed head piece, a spring forcing the tongue piece into the opening in the fixed head piece, a second tongue capable of entering the opening 25 in the limitedly movable head piece, a second spring forcing the second tongue into the opening in the limitedly movable head piece, a projecting part on each of the tongues, arm means pivotally mounted between and capable of contacting with said projecting parts on the tongues to force the tongues backward to release them, a second projecting part on each of the tongues, a cam pivoted between the tongues and operable 30 against the second projecting parts so as to 35 release the tongues from their respective head pieces and a lock means for operating said cam.

6. A locking and barring mechanism for a door comprising holding parts on the door jamb and tongue parts on the door, arm mechanism pivoted between and capable of retracting the tongues from the holding parts, knob mechanism attached to the arm mechanism substantially at its pivotal point capable of operating the arm mechanism first in a clockwise direction to re- 40 tract one tongue and in a counter-clockwise direction to retract the second tongue, and spring mechanism extending between the door and the tongues and capable of returning the tongues to a normal advanced position when they have been 45 retracted by the arm mechanism.

7. A locking and barring mechanism for a door 50 consisting of a chain, a spring attached to the chain and to the door jamb, a headpiece on the chain provided with a groove, a stop-piece on 55 the door jamb provided with a groove, two reciprocable tongue mechanisms on the door, two spring mechanisms forcing the tongues into the grooves of the headpiece of the chain and stop-piece, a reversely movable element to individu- 60 ally retract said tongues from said grooves.

8. A locking and barring mechanism for a door 65 comprising of a chain, a spring attached to the chain and to the door jamb, a headpiece on the chain provided with a groove, a stop piece on the door jamb provided with a groove, two reciprocable tongue mechanisms on the door, two spring mechanisms forcing the tongues into the grooves of the headpiece of the chain and stop-piece respectively, a reversely rotatable element for 70 successively releasing said tongues by reverse movement.

9. A locking and barring mechanism for a door 75 comprising two parts, one attached to the door jamb having a chain, a spring attached to the

chain and to the part, a headpiece on the chain provided with an opening therein, a stop piece provided with an opening therein, and the other said part attached to the door having two reciprocal tongue mechanisms, two spring mechanisms capable of forcing the tongues into the openings of the headpiece of the chain and the stop piece respectively, reversely movable releasing mechanism operable from the inner side of the door adapted by reverse movement to individually and consecutively release the tongues, key operated lock means extending through the door towards the outer side, a connecting bar on and operated by said lock means, and a cam means operable by said lock means to release both of the tongues from said openings practically simultaneously.

10. A locking and barring mechanism for a door, comprising two tongues on the door, projections on said tongues, a single reversely rotatable element, a projection on said element, said element with its projection being located intermediate of the projections on the tongues, and co-operating with the projections on the tongues 15 to retract the tongues individually and successively, and holding elements on the door jamb, one of said holding elements coacting with one of the tongues to hold said door closed and the

other with the other tongue to bar said door in partly opened position.

11. A locking and barring mechanism for a door, comprising two tongues on the door, projections on said tongues, a single reversely rotatable element, a projection on said element, said element with its projection being located intermediate of the projections on the tongues, and co-operating with the projections on the tongues to retract the tongues individually and successively, a holding element on the door jamb co-acting with one of the tongues to hold the door in a closed position, and a spring retracted barring element on the door jamb, said spring retracted barring element coacting with the other tongue to hold the door in partly opened position.

12. A locking and barring mechanism for a door, comprising two tongues on the door, projections on the tongues, a hand actuated element, extensions on said element, said extensions being adjacent to and capable of co-operating with the projections on said tongues, and said element being positioned intermediate of the projections on the tongues and operable in reverse directions to force backward one tongue to the releasing 25 position by turning in one direction and the other tongue by turning in the opposite direction.

SYLVAN ENGEL.
